UNITED STATES PATENT OFFICE.

WILLIAM W. VOSPER, OF TOLEDO, OHIO, ASSIGNOR TO THE SHAW-KENDALL ENGINEERING COMPANY, OF TOLEDO, OHIO, A CORPORATION OF OHIO.

COLLAPSIBLE TAPER-THREAD TAP AND REAMER.

No. 894,863.

Specification of Letters Patent.

Patented Aug. 4, 1908.

Application filed November 2, 1907. Serial No. 400,407.

To all whom it may concern:

Be it known that I, WILLIAM W. VOSPER, a citizen of the United States, and a resident of Toledo, in the county of Lucas and State of Ohio, have invented a certain new and useful Collapsible Taper-Thread Tap and Reamer; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

10 My invention relates to apparatus for use in conjunction with boring-mills, drill-presses, or the like, for the tapping and reaming of metal flanges or other articles; and it has for its object the provision of a 20 simple and highly efficient tool of this class, which is collapsible in its nature, and in which chasers or dies for different sizes of work are interchangeable and automatically operative to cut a taper thread.

25 The operation, construction and arrangement of the parts of the invention are fully described in the following specification, and illustrated in the accompanying drawings, in which,—

30 Figure 1 is a central longitudinal section of the apparatus embodying my invention. Fig. 2 is a transverse section taken on the dotted line $x-x$ in Fig. 1. Fig. 3 is a bottom plan view of the apparatus. Figs. 4 and 5 are side and bottom end views of the tapered chaser-coating plug. Fig. 6 is a side elevation of the apparatus with an extension chaser-bracing ring shown in section thereon, and Fig. 7 is a top plan view of said ring 40 removed from the apparatus and with two chasers in position therein.

45 Referring to the drawings, 1 designates the chaser or die carrying head of the apparatus, which has its upper portion contracted or fashioned to form a stem 2 for attaching to the usual boring-mill or drill-press spindle or other carrying part of the machine with which it is to be associated by a set-screw or in any other convenient manner. The head 1 and its stem are axially bored from the lower or enlarged end thereof to form the socket 3 for the coiled compression-spring 4 and to receive at its outer end the plug 5, which has its outward movement relative to the 55 head influenced by the action of said spring.

Formed in the face or lower end of the head 1 are a plurality of grooves 6, which radiate from the socket 3 and form ways for the reception of the radially movable chasers or dies 7. These chasers are supported within 60 said ways by the bottom ring 8, which is secured to the head by screws 8^a or in any other suitable manner. The inner ends of the chasers 7 seat in registering grooves or races 9 provided longitudinally in the outer 65 end portion of the plug 5, as shown, said grooves or races tapering gradually inwardly toward their outer ends, so that an inward movement of the plug relative to the head will permit a contraction or inward movement of the chasers in accordance with the 70 taper to be given the thread. The grooves or races 9 terminate at their inner ends in a transverse or annular shoulder 10, which contacts with the inner chaser ends to limit the 75 outward movement of the plug 5. The purpose of forming the plug with the grooves or recesses 9 instead of annularly tapering the same, is to provide stock for abutting against the wall of the socket 3 between the points 80 of engagement of the chasers with the plug so as to positively center the chaser-engaging end of the plug within the socket. This has has been found in practice to be an important 85 feature. The relative longitudinal movement of the head 1 and plug 5 is occasioned by the lower end of the plug striking the bed 12 of the press when the head has been lowered in contiguous position to the work and maintaining such fixed position during the 90 continued movement of the head and chasers through the work.

13 designates a stop-screw which is carried at the lower end of the plug 5 and is adjustable in the plug as the depth of the work or 95 diameter of the thread may require.

In order to provide simple means for simultaneously throwing out the chasers 7 after an operation, each chaser is provided on its top with a pin or projection 14, which projects through a radial slot 15 in the roof of the associated chaser groove 9 and into a registering cam-recess 16 provided in the lower end of the sleeve 17. This sleeve is journaled for rotary movement on the contracted portion of the head 1 with its lower end seating on the shoulder 1^a of the head and its upper end abutting against a collar 18, which is threaded to the head, as shown. A handle 19 projects from the sleeve 17 to facilitate a 110

turning thereof. It is thus apparent that when the plug 5 has been forced within the head it is retained in such position by the coacting of the chasers with its tapered surfaces until the sleeve 17 has been turned in the proper direction for the cam-recesses 16 to act on the pins 14 to throw the chasers out.

Referring to Figs. 6 and 7, 20 designates a head extension-ring, which is intended to 10 brace the projected chaser-ends and to adapt the apparatus for operating on a greater range of sizes of work than would otherwise be possible. This ring is intended to fit closely around the enlarged or chaser carrying part of the head 1 and has the upper portion of its inner surface annularly recessed, as at 21, to adapt it to seat over the shoulered portion 1^b of the head periphery, as shown; thus limiting the inward or upward 15 movement of the ring on the head. The under side of the ring is radially recessed or grooved, as at 22, to provide chaser-ways in register with those in the head. A key 23 is positioned in registering seats 24 in the 20 head and ring to lock the same against relative rotation. As the working strain is upward on the chasers it is apparent that the latter need only be braced on the tops or upper sides thereof, as shown.

30 The chasers or dies 7 are shown as having their ends formed with lower reaming surfaces 7^a and upper thread cutting surfaces 7^b, thus making it possible both to ream and thread the work at a single operation.

35 It is apparent that I have provided a very strong and highly efficient apparatus of the class described, which is easy and simple of operation and is capable of adjustment for a very large range of sizes of work, as the extension-rings 20 may be made in different 40 sizes to suit the different lengths of chasers used.

I wish it understood that while I have shown and described a particular construction and arrangement of the parts of my invention, I do not desire to be restricted to such construction or arrangement, as obvious modifications will occur to persons skilled in the art.

50 Having thus described my invention, what I claim as new and desire to secure by Letters Patent, is,—

1. In combination, an axially - socketed head, tapping dies radially movable therein, means mounted for axial movement within the head socket and adapted when moved inwardly therein to permit a retraction of the dies, means influencing an outward movement of said first means, and rotary means carried by the head and acting on the dies independently of said first means to effect a positive radial movement to the dies when the head and said rotary means are relatively turned.

65 2. In combination, an axially - socketed

head, tapping dies radially movable therein, a plug yieldingly mounted in said socket and having a tapered portion coacting with the inner ends of the dies to permit them to gradually retract when the plug is moved inwardly, and a sleeve rotatably carried by the head and acting on the dies independently of the plug to cause an outward movement thereof when the sleeve is rotated in one direction relative to the head.

70 3. In combination, an axially - socketed head, chasers mounted for radial movement in said head, a plug movable in said socket and having tapered longitudinally extending chaser-coacting surfaces whereby a relative 75 movement of the plug and head in one direction permits an inward radial movement of the chasers, a sleeve journaled on the head and having cam-recesses in one end, pins projecting laterally from the chasers and working in said recesses whereby a rotary 80 movement of the sleeve effects a positive radial movement of the chasers, and means for influencing an outward movement of the 85 plug.

90 4. In combination, a head having radial chaser-ways therein and formed with a contracted axial extension forming a stem, said head and its stem being axially socketed, a plug yieldingly mounted in said socket and provided longitudinally with tapered chaser-engaging surfaces, chasers mounted for radial movement in said ways and having lateral projections, a sleeve journaled on the contracted portion of the head and having an 95 end abutting against the shoulder formed by the head proper, said sleeve end having cam-recesses for receiving the chaser projections, and a stop-screw threaded in the outer end of the plug for contact with an alining object to 100 hold the plug stationary to permit the head to move down thereon.

105 5. The combination with a tapping-head having a peripheral shoulder, and the chasers carried by the head, of an extension-ring 110 removably encompassing the head and having an inner recess for receiving the shoulder and radial grooves for receiving the projected chaser-ends, the shoulder and chasers acting in opposition on the ring to retain it in position on the head.

115 6. The combination with a tapping-head, and radial tapping dies carried thereby, of an extension-ring removably encompassing the head and combining with the head to brace 120 the ends of the dies which project beyond the head.

In testimony whereof I have hereunto signed my name to this specification in the presence of two subscribing witnesses.

WILLIAM W. VOSPER.
